BUBBLE PRODUCING TOY

Julius Ellman, 1672 E. 7th St., Brooklyn, N.Y., assignor to Julius Ellman, Brooklyn, and George Lerner, Freeport, N.Y.

Filed Feb. 24, 1959, Ser. No. 794,976

8 Claims. (Cl. 46—7)

This invention relates to toys and, more particularly, to a novel device for producing bubbles.

While various types of bubble-producing devices have been incorporated in toys and amusement devices for children, such have often been associated with stationary or hand carried devices. It is an object of the present invention to provide a toy embodying a bubble-producing device in which the toy itself is propelled so as to enable the bubbles to be discharged in a continuous stream.

Another object of the present invention is to provide a bubble-producing toy having propulsion means which simultaneously effects animation of the toy and energization of the bubble-producing apparatus in response to the passage of air relative thereto caused by such movement of the device.

Still a further object of the present invention is to provide a toy of the type described in the form of a model aeroplane having a propeller that is driven by the movement of the aeroplane in the air, such propeller being drivingly connected to the bubble producing apparatus for producing a continuous jet stream of bubbles simulating the air stream of an authentic aeroplane in flight.

An additional object of the present invention is to provide an animated toy and combined bubble-producing device of particular construction which accumulates a quantity of produced bubbles, carries them along with the unit during movement thereof, and release such bubbles singly to provide a continuous stream of individual bubbles which form a continuous pattern.

All of the foregoing and still further objects and advantages of this invention will become apparent from a study of the following specification, taken in connection with the accompanying drawing, wherein:

FIG. 1 is a perspective view of a bubble-producing toy made in accordance with the present invention in operative use.

FIG. 2 is an enlarged side elevational view of the toy shown in FIG. 1 in a stationary position.

FIG. 3 is an enlarged top plan view of the toy shown in FIG. 1.

FIG. 4 is a front elevational view of the toy shown in FIG. 2.

FIG. 5 is an enlarged fragmentary front elevational view, with parts broken away, of certain parts of the toy illustrated in FIG. 4.

FIG. 6 is a side elevational view of the parts illustrated in FIG. 5.

FIG. 7 is a top plan view of the apparatus illustrated in FIG. 5.

FIG. 8 is an enlarged fragmentary top plan view, with parts broken away, of the bubble-producing mechanism forming a part of the present invention.

Referring now to the drawing, and more particularly to FIGS. 1 to 4 thereof, a bubble-producing toy 10 made in accordance with the present invention is shown to be in the form of a model aircraft having a fuselage 12, a tail section 13, a wing 15, and landing gear 17. A flexible cable 16, which may be twine, string, or wire, is secured to one end of the wing 15 so as to enable the aircraft to be rotated by a child in the manner illustrated in FIG. 1.

The bubble-producing apparatus 20 is in the form of a nose section which forms an integral part of the aircraft and rotatably supports the propeller thereof in a manner

2

hereinafter more fully described. This nose section 20 defines a bubble-producing liquid storage receptacle of substantially segmental hemispherical shape having a central longitudinal axis that is substantially parallel to the direction of movement of the aircraft. A pair of angularly related vertical and horizontal compartment walls 23, 24 extend across the segmental cutout of the receptacle substantially closing the interior thereof together with a flat back wall 22 that is of similar segmental circular shape.

Bearing elements 26 rotatably support a shaft 27 concentric with the central longitudinal axis of symmetry of the nose section 20. A propeller 28 having a pair of diametrically opposite blades is secured to one forward end of the shaft 27, while a bubble ring set 33 having a pair of diametrically opposite annular rings that define film producing apertures is secured to the opposite rear end of the shaft 27. As is more clearly shown in FIGS. 6 and 7 of the drawing, each of the vertical and horizontal 15 compartment walls 23, 24 is provided with communicating slots 30, 31 that lie within the plane of rotation of the bubble ring set 33 so as to accommodate the rotation of the annular rings therethrough, whereby each such annular ring is momentarily exposed within the segmental cutout during each rotation of the shaft 27.

The interior of the receptacle formed by the nose section 20 is filled with a bubble-producing liquid 37 through a slightly enlarged filler opening 36 communicating with the slot 31 in the horizontal compartment wall 24. As 20 a result, each ring of the bubble ring set 33 will receive a film of this bubble-producing liquid as the shaft is rotated by the rotation of the propeller 28 as the toy is rotated through the air in the manner illustrated in FIG. 1. As the film carried by each ring is exposed to the air stream 35 during such flight, a bubble is formed. However, because of the particular relationship between the propeller blades and the ring set, and the shape of the nose section 20, such formed bubbles are not immediately discharged into the air, but accumulate behind the flat rear wall 22 of the nose section and seemingly form a conical cluster 40 with the apex thereof facing rearwardly with respect to the path of movement of the aircraft. The bubbles disposed at the rear apex end of this conical cluster 40 are thus apparently released in a singular manner as additional bubbles 45 are formed by the bubble ring set and are accumulated at the base end of the conical cluster. The result is that a substantially continuous path of apparently single bubbles 42 trail behind the toy as it is propelled through the air so as to simulate the jet stream of an authentic aircraft.

50 Certain interesting features and results will now become apparent with further reference to FIGS. 5 through 8 of the drawing. Because of the novel shape and construction of the nose section 20, with the segmental cut-out portion thereof facing radially inwardly toward the center of rotation of the toy, centrifugal force created by the circular movement of the toy will not spill the bubble producing liquid 37 therefrom since such will move outwardly and upwardly into the substantially semi hemispherical outside section of the nose 20 (FIGS. 4 and 5). 55 Similarly, when the toy is placed upon the ground or tilted 90° sidewise, which enables the toy to be picked up by the string, preparatory to flying without spilling liquid and without messing up the child, such liquid will be substantially confined within the similarly shaped side 60 half section of the nose member 20.

65 It has been found that the most favorable results heretofore explained are attained when the longitudinal axis of the bubble ring set lags approximately forty-five degrees behind the longitudinal axis of the propeller 28 with 70 respect to the direction of rotation of these elements during the forward flight of the toy. When the bubble ring set is in phase with the propeller, the propeller tends to

block the flow of air through the bubble rings and thus tends to interfere with the proper formation of the bubbles. Also, when the bubble rings are further out of phase with the propeller, such as at ninety degrees relative thereto, the bubble formation is not as satisfactory since there is less of a tendency for the bubbles to accumulate in the aforementioned conical form. While the exact reasons for the particular bubble formation are not known, it appears that the bulbous surface of the nose section 20 defines an aerodynamic high pressure area, while the flat surface of the rear wall 22 defines a low pressure aerodynamic surface. This pressure differential seemingly tends to maintain the conical shape of the cluster eccentrically of the nose section 20, and symmetrically with respect to the shape of the segmental circular rear wall 22.

It has also been found that extremely thin bubble rings produce a minimum amount of churning of the bubble solution and thus reduces the production of the fine foam that only creates a mass of small bubbles which are not particularly desirable, and which increases the loss of solution at a very rapid rate, thus making for a very uneconomical device. Accordingly, the periphery of the present bubble producing rings define as much of a knife-like edge as possible to minimize this foam producing effect.

While this invention has been described with particular reference to the construction shown in the drawing, it is to be understood that such is not to be construed as imparting limitations upon the invention, which is best defined by the claims appended hereto.

Having thus described my invention, what I claim as new and desire to secure by Letters Patent is:

1. A bubble producing device comprising, in combination, a substantially closed storage receptacle for containing a quantity of bubble producing liquid, means for moving said storage receptacle through the air in a predetermined direction, a bubble ring set supported for rotation into and out of said receptacle for receiving a film of bubble liquid therefrom, said bubble ring set defining a plurality of spaced film producing apertures and having an axis of rotation extending parallel to said direction of movement of said storage receptacle, said bubble ring set lying within a plane substantially normal to said predetermined direction of movement of said receptacle, said storage receptacle having openings only large enough for free passage therethrough of said bubble rings and drive means coaxial with but axially spaced apart from said bubble ring set, said drive means being responsive to the relative passage of air past said storage receptacle effecting rotation of said bubble ring set, said means for moving said storage receptacle through the air comprising a model aircraft having a fuselage, a tail unit, and a wing, said receptacle being secured to said fuselage, and a flexible cable secured at one end to one end of said wing for actuation at the opposite end of said cable for swinging said model aircraft in a circular path.

2. A bubble producing device as set forth in claim 1, wherein said storage receptacle is of substantially seg-

mental hemispherical shape having a central longitudinal axis substantially parallel to said direction of movement with the bulbous surface thereof facing forwardly toward said direction of movement, and said bubble ring set being supported within said receptacle for rotation about said central axis, the inside diameter of said receptacle being greater than the length of the diameter of said bubble ring set, and a segmental cut-out in said receptacle exposing said bubble ring set during each revolution to air passing parallel to said path of movement.

3. A bubble producing device as set forth in claim 2, further comprising angularly related flat walls extending across said segmental cut-out substantially closing the interior of said storage receptacle, and aligned slots in each of said flat walls in the plane of rotation of said bubble ring set accommodating said rotation of said bubble ring set therethrough.

4. A bubble producing device as set forth in claim 3, wherein said drive means comprises a propeller, a shaft rotatably supported upon said receptacle concentric with said longitudinal axis, said propeller being secured to one forward end of said shaft, and said bubble ring set being secured to the opposite end of said shaft, whereby rotation of said propeller effects rotation of said bubble ring set.

5. A bubble producing device as set forth in claim 4, wherein said propeller comprises a pair of diametrically opposed blades, said bubble ring set comprising a pair of diametrically opposed rings each defining one of said apertures, said bubble ring set being out of phase with and lagging said propeller.

6. A bubble producing device as set forth in claim 5, wherein the longitudinal axis of said bubble set defines a lagging angle of substantially forty-five degrees with the longitudinal axis of said propeller.

7. A bubble producing device as set forth in claim 6, further comprising means for accumulating bubbles upon the exterior of said receptacle and releasing them singly in a continuous stream therefrom in response to said movement of said receptacle.

8. A bubble producing device as set forth in claim 7, wherein said accumulating means comprises a substantially flat rear wall facing rearwardly with respect to said direction of movement, said bulbous surface of said receptacle defining a high pressure aerodynamic surface area and the area behind said flat rear wall defining a low pressure area creating a conical formation of trailing bubbles having a rearwardly directed apex, said bubbles being retained in such formation by a differential air pressure, and the bubbles forming said apex continuously being released by the continued build-up of the base of the conical formation in response to the formation of additional bubbles during said movement of said receptacle.
